UNITED STATES PATENT OFFICE.

HARRY A. OKEL, OF PLEASANTON, WEST VIRGINIA, ASSIGNOR TO THE FERDINAND STRAUSS CORPORATION, OF NEW YORK, N. Y., A CORPORATION OF NEW YORK.

MECHANICAL CLOWN TOY.

Application filed June 21, 1927. Serial No. 200,317.

This invention relates to improvements in mechanical clown toys and has for one of its objects the provision of such a toy of simple and inexpensive construction and one that will amuse children.

Another object of the invention is to provide a toy of this nature having a drum rotatably supported on a stand or the like, the said drum having swingingly supported therefrom a figure of a clown adapted to perform various acrobatic stunts when the drum is revolved.

Other objects and novel features of construction of my invention will become apparent as the specification proceeds.

In the drawings forming a part of this specification, I have shown a preferred form of my invention in which

Figure 1 is an end view in elevation of my improved toy with one of the end closures removed and a portion of the motor casing broken away.

Figure 2 is a sectional view taken on line 2—2, Fig. 1 and

Figure 3 is a fragmental plan view showing how the toy figure is mounted on the drum.

Referring to the drawings in detail 5 indicates a hollow drum preferably made of thin sheet metal to the rear end wall 6 of which there is suitably secured as by soldering for instance, a motor casing 7, in which is suitably mounted a motor mechanism 8 comprising a winding key shaft 9 rotatably mounted in the end walls 10 and 11 of the motor casing 7, a ratchet 12 secured to the shaft 9, a power spring 13 anchored at one end to the said ratchet 12 and at its opposite end to a drive gear 14 loosely mounted on the key shaft 9, a pinion 15 in mesh with the drive gear 14 and secured to a gear 16 rigidly mounted on a horizontal shaft or extension 17 of a supporting stand 18 upon which the drum 6 and the motor casing 7 is rotatably supported. The gear 16 meshes with a pinion 20 secured by a hub 21 to a gear 22 fast on a shaft 23 rotatably journaled in the motor casing 7 and the said gear 22 meshes with a pinion 24 secured to a governor shaft 25 rotatably mounted in the casing 7 and having a governor disk 26 mounted thereon to regulate the speed of the motor.

The drum 5 is provided with a pair of ears 27—27 through which passes a suspension

wire 28 loosely supporting the hands or arms 29 of a toy clown figure 30. The said arms 29 are loosely mounted on a split pin 31 passing through the body 32 of the figure and the arms 29. A washer 33 on each side 60 of the body 32 space the arms from the body. Legs 34 are similarly supported on the body by a pin 35. A counterweight 36 secured to the inside of the drum 5 tends to maintain the toy in proper equilibrium when revolved.

The action of the toy is as follows: When the spring 13 is wound up it will rotate the gear 14 which will in turn revolve around the pinion 15 and gear 16 on the shaft 17 70 and cause the drum and motor mechanism to rotate on the said shaft in the direction of the arrow (Fig. 1) and carry the figure 30 with the said drum and cause it to perform various acrobatic stunts as for instance 75 a somersault as indicated in dot and dash lines. The gears 16 and 22, and the pinions 20 and 24 actuate the governor 26.

From the foregoing it will be seen that I have provided a toy of simple and efficient 80 construction and one that will amuse and give pleasure to children.

While I have shown a preferred form of my invention, I desire it understood that I do not limit myself to the exact construction 85 shown as many variations and changes may be had without departing from the scope of the appended claims.

Having described my invention, what I claim as new and desire to secure by Letters 90 Patent is:

1. In a toy of the nature described, a support, a drum rotatably mounted thereon, a motor in the drum for rotating same about the support, and a jointed figure swingingly 95 suspended from the drum adapted to perform acrobatic stunts substantially as described when the drum is rotated.

2. In a toy of the nature described, a support, a drum rotatably mounted thereon, a 100 casing secured to the drum and rotatably mounted on the support, a motor mechanism in the casing to rotate the drum about the support and a jointed figure suspended from the drum to rotate therewith and perform 105 acrobatic stunts when rotated.

3. In a toy of the nature described, a support, a drum rotatably mounted thereon, a casing secured to the drum and rotatably mounted on the support, a motor mecha- 110

nism in the casing to rotate the drum about the support, a figure support on the drum and a toy figure having arms and legs pivotally secured to the body portion thereof and loosely suspended by the arms from the said support to rotate with the drum and perform acrobatic stunts when rotated.

4. A toy comprising a support, composed of a rod formed into a base part, an upright part and a horizontal shaft part; a drum

rotatably mounted on said shaft part and having a substantially closed periphery; ears on said periphery; an articulated figure pivoted to said ears and adapted at times to lie on the periphery of said drum and be 15 carried over with the same; and a spring motor within the drum for imparting rotation thereto.

HARRY A. OKEL.
